DISPOSABLE DUST RECEPTACLE FOR
BRUSH TYPE CARPET SWEEPERS

George M. Parker, Shelbyville, Ind., assignor to
Hester Porter Fuller, George M. Parker, and
Parrish Fuller, a co-partnership, doing busi-
ness under name and style Porter Steel Spe-
cialties, Shelbyville, Ind.

Application September 5, 1939, Serial No. 293,422

3 Claims. (Cl. 15—41)

In that type of carpet sweeper characterized by a rotary brush rotatably mounted within a casing supported by traction wheels which permit reciprocating transportation of the casing at right angles to the brush axis accompanied by brush rotation, dirt-receiving pans are arranged within the casing, one along each side of the brush in position to receive and retain the sweepings. Generally these pans are tiltable about axes parallel with the brush axis to discharge accumulated sweepings.

Disposal of debris from sweepers of this type is a somewhat messy operation and, in many instances, mere tilting of the dust pans is not sufficient to entirely discharge debris therefrom. In any event the clearing operation involves the necessity of providing a receiver of some kind, often a piece of newspaper, and the probability of scattering of some of the debris during the operation.

The object of my invention is to provide a carpet sweeper structure and associated debris receptacle of such character that the debris receptacle with its accumulated debris may be readily bodily extracted from the sweeper casing and disposed of as a unit.

The accompanying drawing illustrates my invention:

Fig. 1 is a perspective view of a carpet sweeper embodying my invention;

Fig. 2 is a vertical section in a plane at right angles to the axis of the brush;

Fig. 3 a perspective of my improved debris receptacle extracted from the casing of the sweeper; and

Fig. 4 a plan, on a smaller scale, of a blank from which the disposable debris receptacle may be formed.

In the drawing 10, 10 indicate usual traction wheels between which is mounted the rotary brush 11 driven by said wheels. The wheels support a casing 12 which envelopes the brush, and which is substantially like casings ordinarily found in sweepers of this type but differs therefrom in that it has no fixed top overlying the brush and adjacent regions of the interior of the casing flanking the brush along each side.

The details of wheel mounting and brush mounting and driving form no part of my present invention and may be of any desired construction well known in the art.

Flanking each side of the brush at the bottom of the casing are supports 13 extending from close to the brush to the front and rear walls of the

casing. These supports may be tilting dust pans commonly found in sweepers of this type or may be fixed debris-retaining or non-debris-retaining.

Supported by the supports 13 are pan-shaped receptacles A, A made of paper or other light flexible and cheap material and connected between the upper ends of their outside walls by the same material.

Conveniently my debris receptacle is formed from a paper blank comprising the middle connecting portion 15, the outside walls 16, 16, the bottoms 17, 17, the inner walls 18, 18, the end walls formed by overlapping a flap 16' carried by the outside walls, a flap 17' carried by the bottom and a flap 18' carried by the inside walls, these 15 various parts being defined by fold lines as indicated in Fig. 4.

Secured to each inside wall, preferably near each end wall, are the two ends of a string 19, the middle of which overlies portion 15 and passes through perforations 20 which may be conveniently defined by eyelets to avoid tearing.

The paper pans, when in place within the casing, rest upon or in the supports 13 in position to receive the sweepings discharged by the brush, while the intermediate connecting portion 15 of the structure overlies the open mouths of the pans and the intermediate brush.

If desired, casing 12 may be provided with a readily movable or removable cover 25 to overlie the disposable debris receptacle described above.

In use the pans of the disposable (or removable) debris receptacle, will receive and retain the brush sweepings. In due course the user, grasping the middles of the strings 19, may lift the disposable structure bodily from the casing, the pan structures swinging on the fold lines between the outside walls and the connector 15 until the upper edges of their inner walls engage the under face of connector 15 thereby entrapping the contents 40 of the pans so that spilling is impossible.

Because of the low cost of this disposable structure it may, when changed and removed, be conveniently thrown into the garbage, or incinerator, or furnace, though economically inclined persons may dump the contents and re-insert in the sweeper casing.

I claim as my invention:

1. For a carpet sweeper of the rotary brush type 50 and having substantially horizontal platforms flanking the brush below the center thereof, a removable debris receptacle formed of flimsy, inexpensive, readily discardable material and comprising, a pair of parallel pan-like receptacles 55

capable of flanking the sweeper brush and restable on the brush-flanking platforms of the sweeper, a readily flexible connector overlying and connecting said receptacles, and means cooperating with said receptacles and operable, upon removal of said receptacles from said sweeper, to close said pan-like receptacles against accidental discharge of dirt therefrom.

2. For a carpet sweeper of the rotary brush type and having substantially horizontal platforms flanking the brush below the center thereof, a removable debris receptacle formed of flimsy, inexpensive, readily discardable material comprising, a pair of parallel pan-like receptacles capable of flanking the sweeper brush and restable on the

brush-flanking platforms of the sweeper, a readily flexible connector overlying and connecting said receptacles, and means accessible from above the connector and connected to the adjacent sides of the pans by which the structure may be lifted to bring the adjacent sides of the pans into closer and abnormal relation with the under surface of the connector.

3. A device of the character specified in claim 2 made of sheet material such as paper and wherein the lifting means comprise flexible elements passed through the connector and attached to the pans at points inwardly spaced from the connections of the pans with the connector.

GEORGE M. PARKER. 15
